FILLING MACHINE

Edward Percival Wilson, London, England, assignor to Lancashire Dynamo & Crypto Limited, London, England

Application December 27, 1939, Serial No. 311,101
In Great Britain January 19, 1939

7 Claims. (Cl. 17—37)

This invention relates to filling machines and more especially to machines for filling sausages, and has for an object to provide an improved machine of simple and efficient construction which may be driven by hand or by motor and which is much less cumbersome than the usual filling machines and which can be rapidly and effectively cleaned after use.

The filling machine of the invention comprises a cylindrical container for the filling material in which is mounted a central shaft fitted with a vane adapted to sweep the cylinder from one face to another of a second vane of wedge or segmental form secured within the container and extending from end to end thereof and towards the central shaft, this second vane being provided with a port in its face leading to a discharge outlet disposed externally of the container. To the discharge outlet is attached the usual filler tube receiving the article to be filled. The shaft is driven through worm reduction gearing having a high ratio by a handle or a motor.

To avoid the necessity for returning the vane to the starting point each time the container is discharged in order to commence a new filling operation, the fixed vane may be provided with ports on each face and a hollow sleeve with a single port may be rotatably mounted within the vane the sleeve being rotated after each discharge operation through 180° to bring the port in the sleeve into register with the port on the opposite face of the fixed vane so that the container can be filled again and return movement of the vane made use of to discharge such filling material.

In order to protect the gearing, particularly where an electric motor drive is used, a clutch may be provided which is adapted to slip, say when the movable vane on its movement has contacted with the surface of the fixed vane.

Two embodiments of a sausage filling machine constructed in accordance with the present invention are illustrated in the accompanying drawings, in which Fig. 1 is a cross-section through the container of a machine in accordance with a first embodiment, while Fig. 2 is a horizontal section. Fig. 3 is a side elevation of a machine constructed in accordance with a second and preferred embodiment of the invention. Fig. 4 is a plan view thereof; Fig. 5 a horizontal section showing the driving mechanism; Fig. 6 is a horizontal section through the container; while Fig. 7 is a vertical cross-section through the complete machine.

Referring now to Figs. 1 and 2 of the drawings,

1 denotes a cylindrical container for the sausage meat, while 2 denotes a shaft centrally mounted within the cylinder 1 and fitted with a vane 3 extending substantially to the inner wall of the container. The container is provided with a removable cover plate 4 which also serves as a bearing for one end of the shaft 2. Within the container is secured a second vane 5 of segmental or wedge form extending to the surface of the shaft 2 and extending from the top to the bottom 10 of the container 1. The vane 5 is provided with a port 6 in one of its faces, which port leads to a discharge outlet 7 in a screw threaded extension 8 located externally of the container 1. To the extension 8 is attached by means of a nut 9 15 the usual filler tube 10 receiving the sausage casing to be filled. The container 1 is closed at the bottom by a hollow pedestal 11 forming a gear box within which is mounted a worm 12 which meshes with a worm wheel 13 mounted on 20 the shaft 2, the worm and worm wheel constituting a reduction gearing which is adapted to be driven by means of a handle or a motor (not shown), the handle or power-transmission coupling fitting on the squared end 13a of the shaft 25 of the worm 12. The cover plate of the container 1, and the pedestal 11 are secured together by bolts (not shown).

In use of the apparatus sausage meat is filled into the container 1 on one side of the movable 30 vane 3 which is moved by rotation of the shaft into contact with one side of the vane 5 and the cover plate 4 is clamped in place. The shaft 2 is then rotated. As the vane 3 moves with the shaft 2 the sausage meat inserted between it and 35 the other surface of the fixed vane 5 is forced through the port 6 in the latter and through the filler tube 10. By virtue of the segmental form of the fixed vane 5 with its radially disposed surfaces, the sausage meat is entirely discharged 40 from the container 1. Any air between the movable vane 3 and the fixed vane 5 may escape between the movable vane 3 and the inner surface of the container 1.

After the contents of the container 1 have been 45 discharged the vane 3 is returned to its starting point before the container is refilled.

The necessity for returning the vane 3 to its original position is obviated in the embodiment illustrated in Figs. 3 to 7. Referring now to Figs. 50 3 to 7, 1' denotes the container secured by bolts 14 to a pedestal 11' incorporating a gear box. On diametrically opposite sides of the container 1' and rotatably mounted in brackets 15 cast thereon, are two curved arms 16 which are tapped 55

to receive square-threaded clamping screws 17. These clamps 17 serve to hold down the cover-plate 4' and can be released and swung to one side, as indicated by the dotted lines in Fig. 3 to allow cover-plate 4' to be lifted off. The cover-plate 4' is spigotted to fit the container 1' and has two laterally projecting portions 4a constituting hand-grips to facilitate removal of the cover-plate 4' from the container 1'. The vertical rotatable shaft 2' extends through a bearing provided in the upper surface of the pedestal 11' and is provided with a bearing surface at the other end in the cover-plate 4'. The shaft 2' is slotted at 18 to receive the flat vane 3' which is secured firmly to shaft 2' by means of rivets 19.

The fixed vane 5' of wedge or segmental form is shaped to fit closely the inner circumference of the container 1', the shaft 2' and, on its flat top face 5a and its bottom face 5b, the cover-plate 4' and the pedestal surface 11' respectively. The vane 5' is held in position by means of two opposing positioning pins 20, one projecting through the cover-plate 4' and the other projecting through the upper surface of the pedestal 11'. These pins 20 are disposed offset so as to prevent twisting of the vane 5'. The vane 5' is further secured by means of a rotatable and withdrawable sleeve 8a positioned within a boss 21 on the exterior of the container 1'. This sleeve 8a is screwed to receive the usual clamping nut 9' for holding the filler tube 10' in position. The sleeve 8a is provided with two diametrically-disposed holes 22 for the reception of the end of a plunger 23 slidably mounted in the boss 21. The movement of plunger 23 is restricted by means of a grub screw 24 the point of which engages in a slot in the plunger 23.

The vane 5' is provided with a slot 25 adapted to register with a co-incident aperture 26 in the sleeve 8a.

The machine can be operated manually or driven by power. A preferred form of hand operated gear shown in the drawings operates as follows.

45 A shaft 27 carrying the worm 12' is mounted in bearings in pedestal 11' and is provided with a squared end 28 to receive a crank handle (not shown). End thrust is taken up by a double thrust washer 29. A worm wheel 13' is keyed to shaft 2', this shaft being further supported by a cover-plate 30 and top plate 4'. A plug 31 is provided for the admission of lubrication oil to the gearbox. Rotation of the worm 12' in one direction will lift oil from the gearbox and deposit it 55 in the cone-shaped top of worm wheel 13' from which the oil may pass through the channel 33 to the bearing of shaft 2'.

The bottom of the container 1' constituted by the top of the pedestal 11' is raised or stepped as 60 at 32 to reduce the possibility of water working down the shaft 2' into the driving mechanism. To reverse the machine it is simply necessary to turn the crank handle in the opposite direction.

An arrow 34 is marked on the top of shaft 2', 65 in line with vane 3' and two arrows 35 are marked on the cover-plate 4' to indicate the two extreme positions of vane 3'. The position of arrow 34 in relation to the arrows 35 will provide the operator with an indication of the amount of meat 70 left in the container 1'.

The cycle of operations is as follows:

The rotatable vane 3' is rotated by rotation of the worm shaft 27 until it lies flat against fixed vane 5' in position 3a shown in dotted lines in 75 Fig. 6. The container 1' is filled with sausage

meat and the cover-plate 4' placed in position and held down by clamps 17. The vane 3' is then rotated and meat is forced through the slot 25 in vane 5', through the aperture 26 in sleeve 8a and out of the filler tube 10'. When the container 1' is empty, the plate 4' is removed and the machine re-filled. The plunger 23 is withdrawn from one of the holes 22 and the sleeve 8a rotated 180° by means of the nut 9', thus bringing the aperture 26 opposite the other side of the slot 25 in vane 5'. The sleeve 8a is then locked in this position by replacing the plunger 23 in the other hole 22. The operator can then proceed to wind the vane 3' in the reverse direction, the meat being forced out as previously described.

To clean the machine, cover-plate 4' and sleeve 8a are removed and vane 5' lifted out. These parts can be separately washed and the container 1' washed out, any dirty water escaping from a slot 36 which is uncovered when vane 5' is removed.

I claim:

1. A filling machine comprising a cylindrical container for the filling material, a stationary vane of wedge form secured within said container and having a port on at least one of its faces, a shaft mounted for oscillation within said container, a vane mounted on said shaft and adapted to sweep said container from one face to another of said stationary vane and to push the filling material through said port and a filling nozzle disposed externally of the container in communication with said port for receiving the contents of the container. 35

2. A filling machine comprising a cylindrical container for the filling material, a stationary vane of wedge form secured within said container and having ports on opposite wedge faces communicating with a common outlet passage, a shaft mounted for oscillation within said container, a vane mounted on said shaft and adapted to sweep said container from one face to another of said stationary vane and to push the filling material through one of such ports and a filling nozzle disposed externally of the container and connected to said outlet passage for receiving the contents of the container. 45

3. A filling machine comprising a cylindrical container for the filling material, a shaft centrally mounted for oscillation within said container, a vane mounted to oscillate with said shaft and adapted to sweep said cylindrical container in its oscillation, a stationary vane of segmental form secured within said container and extending to adjacent the periphery of said shaft, said stationary vane presenting abutment faces to the oscillating vane and having a port in at least one of its abutment faces communicating with the exterior of the container, and an outlet fitting disposed externally of the container and in communication with said port for receiving the contents of the container. 55

4. A filling machine comprising a cylindrical container for the filling material, a shaft centrally mounted for oscillation within said container, a vane mounted to oscillate with said shaft and adapted to sweep said container in its oscillation, a stationary vane of segmental form secured within said container and extending to adjacent the periphery of said shaft, said stationary vane presenting abutment faces to the oscillating vane and having ports in its abutment faces communicating with the exterior of the container, and an outlet fitting disposed externally 70 of 75 75

of the container and adapted to be brought in register with one of said ports to permit the contents of the container to be discharged.

5. A sausage or like filling machine comprising a cylindrical container for the filling material, a shaft centrally mounted for oscillation within said container, a vane mounted to oscillate with said shaft and adapted to sweep said container in its oscillation, a stationary vane of segmental form secured within said container and extending to adjacent the periphery of said shaft, said stationary vane presenting abutment faces to the oscillating vane and having ports in its abutment faces and an adjustably mounted sleeve extending externally of the container and having a port adapted to be brought in register with one of said first mentioned ports to permit the contents of the container to be discharged.

6. A filling machine comprising a cylindrical container for the filling material having a base and a cover, a shaft centrally mounted for oscillation within said container and having a bearing in said cover, a vane mounted to oscillate with said shaft and adapted to sweep said container in its oscillation, a stationary vane of segmental form extending to adjacent the periphery of said shaft and secured within said container by pins extending from said cover and said base, said pins being offset in relation to one another, said stationary vane presenting abutment faces to the oscillating vane and having ports in its abutment faces communicating with the exterior of the

container, a rotatably mounted sleeve extending externally of the container and adapted to be brought into register with one of said ports to permit the contents of the container to be discharged and means for locking said sleeves with its port in register with either of the ports in the stationary vane.

7. A filling machine comprising a cylindrical container for the filling material having a base having a central raised portion and formed by a pedestal and a cover, a shaft centrally mounted for oscillation within said container having a bearing in said cover and extending through said base, gearing mounted in said pedestal for oscillating said shaft, a vane mounted to oscillate with said shaft and adapted to sweep said container in its oscillation, a stationary vane of segmental form extending to adjacent the periphery of said shaft and secured within said container by pins extending from said cover and said base, said pins being offset in relation to one another, said stationary vane presenting abutment faces to the oscillating vane and having ports in its abutment faces communicating with the exterior of the container, a rotatably mounted sleeve extending externally of the container and adapted to be brought into register with one of said ports to permit the contents of the container to be discharged and means for locking said sleeve with its port in register with either of the ports in the stationary vane.

EDWARD PERCIVAL WILSON.
